UNITED STATES PATENT OFFICE.

NEWTON JAY BEAZLEY, OF SELMA, ALABAMA.

SHOCK ABSORBER.

Application filed July 10, 1924. Serial No. 725,245.

To all whom it may concern:

Be it known that I, NEWTON JAY BEAZLEY, a citizen of the United States, residing at Selma, in the county of Dallas and State of Alabama, have invented certain new and useful Improvements in Shock Absorbers, of which the following is a specification, reference being had to the accompanying drawings.

10 This invention relates to certain improvements in shock absorbers and it is an object of the invention to provide a novel and improved device of this general character constructed and operating in a manner to eliminate any side sway and of rear and front sway of the vehicle body.

Another object of the invention is to provide a novel and improved device of this general character which coacts directly with 20 the spring of the vehicle together with an adjacent axle or housing and operates in a manner to prevent breakage of the spring when subjected to undue stress or strain.

An additional object of the invention is 25 to provide a novel and improved device of this general character which will not have a tendency to throw the rear axle out of proper alignment and thereby tend to break the motor supports, one that will perform

30 quickly and also act as a snubber.

It is also an object of the invention to provide a device of this general character embodying novel and improved means for securing or attaching the same to the axle, 35 said connection or attachment also serving to provide an efficient means of fastening the radius rod to the axle.

The invention consists in the details of construction and in the combination and arrangement of the several parts of my improved shock absorber whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to de-

scribe the same with reference to the accompanying drawings, wherein:-

Figure 1 is a fragmentary view in elevation with a part in section illustrating a shock absorber constructed in accordance 55 with an embodiment of my invention and applied to the front axle of a motor vehicle;

Figure 2 is a detailed sectional view taken substantially on the line 2-2 of Figure 1;

Figure 3 is a view in top plan of the rocker arm support as herein embodied and unapplied;

Figure 4 is an enlarged view in top plan of the rocker arm as herein disclosed unapplied;

Figure 5 is a view in elevation with a portion broken away illustrating an embodiment of my invention for use in connection with a rear spring of a motor vehicle;

Figure 6 is a view in top plan of the rocker arm as disclosed in Figure 5 unapplied.

As disclosed in the accompanying drawings, A denotes the front axle of a motor driven vehicle and S the semi-elliptic spring of a well-known type positioned above the 75 axle and which is operatively connected with the body of the vehicle (not shown) in any conventional manner.

Resting upon the axle A in desired position is a support 1 for the rocker arm R, said support being disposed lengthwise of the axle A and having its inner end portion provided with an upstanding lug 2 with which the arm R is directly engaged. The inner end portion of the support 1 is also provided with the oppositely disposed and laterally directed stop lugs 3 operating to limit the extent of swinging movement of the rocker arm R in one direction. The outer extremity of each of the lugs 3 is provided with a depending flange 4 and thereby providing means for maintaining the support 1 in applied position.

The opposite or outer end portion of the support 1 is provided with an opening 5 through which is adapted to be disposed from below the anchoring bolt 6, said bolt being also disposed from below through the axle A. The lower end portion of the bolt 6 has a tapered head 7. Coacting with the 100

upper portion of the bolt and the upper surface of the support 1 is the nut 8.

As particularly illustrated in Figure 1 of the accompanying drawings, this bolt 6 is also disposed upwardly through the outer end of the radius rod 9 and the head 7 of the bolt engaging therewith in a manner to effectively maintain said end portion of the rod 9 in firm connection with the axle A.

10 By having the nut 8 at the top it is possible to tighten the rod 9 against the axle A by drawing the head 7 up against the radius rod without turning the head 7 and also the vibrations due to the vehicle when in transit

15 will not loosen the radius rod connection with the resultant rattling as all of the strain will be upon the head 7 and the liability substantially eliminated of the nut 8 being stripped from the bolt 6.

20 The rocker arm R is substantially L-shaped in form with its foot portion comprising a pair of spaced wings 10. The lug 2 extends upwardly between the inner portions of said wings 10 and is pivotally en-

25 gaged therewith by the bolt 11 or the like whereby the arm R is supported for swinging movement in a vertical direction. The eye 12 carried by the adjacent end of the spring S is disposed between the outer ends 30 of the wings 10 and through which is disposed the bolt 14 also extending through and supported by the wings 10. The stem portion of the rocker arm R comprises a pair of transversely spaced arms 15 the outer or 35 free end portions of which being substantially in parallelism and arranged at opposite sides of the spring S.

40 Straddling the spring S from below and a predetermined point inwardly of the eye 12 is a saddle 16 held in applied position through the medium of the bolt 17. The saddle 16 at opposite sides is provided with outstanding plates 18 overlying the outer end portions of the arms 15 of the rocker 45 arm R and interposed between each of said plates 18 and the outer end of an arm 15 is a coil spring 19 of requisite tension.

50 The embodiment of my invention as illustrated in Figures 5 and 6 is substantially the same as hereinbefore described except that the rocker arm support 1^a is directly associated with a rear axle housing and is disposed longitudinally on such curvature as to have requisite close contact therewith, 55 the outer end portion of said support 1^a being anchored or secured in applied position by the bolt 20.

60 When the spring S compresses the arms 15 of the rocker arm R exert an upward thrust against the underside of the spring S through the coil springs 19, thus supporting the spring S and relieving the same of a large portion of the strain imposed thereupon and thereby minimize the liability of said spring breaking.

The lugs 3 prevent the rocker arm or more particularly the arms 15 being swung too far downwardly and when said arms 15 come into contact with the lugs 3, the springs 19 then take up the shock and exert 70 an upward force against the underside of the spring S. The location of the saddle 16 is such that the liability of breakage of the spring S is substantially eliminated.

75 The springs 19 operate to relieve the adjacent outer end of the spring S of leverage action and when the spring S rebounds sufficiently it comes back to a shorter length and again forces the arms 15 into contact with the stop lugs 3. At this time the device 80 begins to act as a snubber in that the spring S cannot shorten any further and the axle A and associated wheels must be picked up if the rebound of the car is sufficient. For this reason the car or vehicle is prevented 85 from turning or swinging sideways as the device at one side will work as a snubber while the device at the other side will work as a shock absorber.

90 As is believed to be obvious from the foregoing description and the disclosure in the accompanying drawings, the spring S cannot stretch out without working my improved device nor can weight or a quick spring at an end of the spring S be applied 95 without the adjacent device functioning.

100 The end of the spring S goes down when weight is applied or when the axle A is forced up causing the rocker arm R to compress the coil springs 19 while at the same time the spring S at the point where the saddle 16 is positioned comes down and further compresses the springs 19. This double action is much quicker than a single action 105 and therefore catches the shock before bounce can happen. It also releases as quickly and thereby prevents a strong rebound.

110 In claiming my invention reference thereto to an axle is to be understood as being 110 the equivalent of a housing or other element with which the device may be employed.

115 From the foregoing description it is thought to be obvious that a shock absorber constructed in accordance with my invention is particularly well adapted for use by reason of the convenience and facility with which it may be assembled and operated, and it will also be obvious that my invention is susceptible of some change and modification 120 without departing from the principles and spirit thereof and for this reason I do not wish to be understood as limiting myself to the precise arrangement and formation of the several parts herein shown in carrying out my invention in practice except as hereinafter claimed.

125 I claim:

130 In a shock absorber, in combination with an axle and a spring, a substantially L-

shaped rocker arm, a support mounted upon the axle, means for holding the support in applied position, means for pivotally connecting the foot portion of said rocker arm to the support, means for connecting the extremity of the spring to the foot portion of the rocker arm, an expansible medium interposed between the stem portion of the

rocker arm and the spring, and an outstanding lug carried by the axle for limiting the swinging movement of the stem portion of the rocker arm in a direction toward the axle. 10

In testimony whereof I hereunto affix my signature.

NEWTON JAY BEAZLEY.
